CLAIM

The ornamental design for a boring machine with casing driver, as shown and described.

DESCRIPTION

FIG. 1 is a front view of a boring machine with casing driver of my new design;

FIG. 2 is a rear view thereof;

FIG. 3 is a left view thereof;

FIG. 4 is a right view thereof;

FIG. 5 is a top view thereof, a bottom view is omitted because the article is a heavy object;

FIG. 6 is a reference view showing a state of use thereof;

FIG. 7 is a partial top reference view thereof with the 8-8 line;

FIG. 8 is a cross-sectional reference view taken along the 8-8 line in FIG. 7;

FIG. 9 is a reference view showing the front thereof with the 1.0-10 line; and,

FIG. 10 is an enlarged cross-sectional reference view taken along the 10-10 line in FIG. 9.

The broken lines in the figures are for the purpose of illustrating portions of the article that form no part of the claimed design.
